DISH-SUPPORTING RACK

Theodore Tafel, Jr., Ben Avon, Pa., assignor to
Standard Sanitary Manufacturing Company, a
corporation of New Jersey

Application October 16, 1931, Serial No. 569,212

4 Claims. (Cl. 141—9)

This invention relates to machines for washing dishes and the like wherein the objects to be washed are placed in an openwork rack and are successively subjected to sprays of soapy water which cleanses the dishes and rotates the rack, and in particular, to improvements in the construction of the rack.

One object of this invention is to provide a dish-supporting rack for a dishwashing machine in which the parts of the rack subjected to wear may be removed and replaced.

Another object is to provide a dish-supporting rack for a dishwashing machine in which novel means for retarding the speed of rotation of the rack are provided so that the dishes will be subjected to the most effective and efficient scrubbing action of the water.

A further object is to provide an openwork wire rack having a lower section and an upper section in which novel means are provided for supporting the upper section on the lower section.

A still further object is to provide novel means for lubricating the rotating rack in a dishwashing machine.

A still further object is to provide an openwork wire rack of improved construction which is easy to manufacture and relatively cheap in cost.

These and other objects which will be made apparent to those skilled in this particular art are accomplished by means of this invention, one embodiment of which is described in the following specification and illustrated in the accompanying drawings, wherein:

Figure 1 is a front view in section of a dishwashing machine provided with a rack embodying my invention, portions of the washing chamber and rack being broken away for convenience of illustration;

Fig. 2 is a view in elevation of the rack;

Fig. 3 is a partial view in perspective showing the means for supporting the upper section of the rack on the lower section; and

Fig. 4 is a view in section of the rack-supporting bearing and associated pin.

Referring to the drawings in detail, 10 designates a portion of a sink, or other kitchen fixture, having a dishwashing chamber or compartment 11 formed integral therewith. Leading from the bottom of the compartment or chamber 11 is a drain pipe 12 having a valve 13 for closing and opening the drain. The valve 13 is operated by a hand lever 14 mounted on the upper portion of the sink 10. The drain 12 is connected above the valve 13 to the inlet side of

a centrifugal pump 15 that is driven by an electric motor 16. The outlet side of the pump 15 is connected to a nozzle 17 which is secured to the bottom of the washing compartment 11 and extends upwardly therein. From this construction it is apparent that when the dishwasher is in operation water is drawn from the chamber 11 by the pump 15 and forced into the chamber through the nozzle 17. The washing water leaving the nozzle strikes against the dishes in a rack 18 which is rotatably mounted on a pin 19 extending upwardly from the bottom of the chamber 11, cleansing the dishes and imparting rotational movement to the rack.

My improved dish-holding rack 18 comprises 15 an openwork basket 20 which is adapted to receive the plates and larger pieces of table ware, an upper tray 21 in which the cups, saucers and the lighter pieces of table ware are placed, and an inner container 22 in which the silverware 20 and the like is received.

The basket 20 is of openwork construction so as to permit the free access of water therethrough and is formed of a series of concentric rings 23 which are spaced apart vertically to 25 form the side wall of the basket. The rings 23 are held in their spaced relationship by vertical extending members or posts 24 which are spaced circumferentially around the rings 23 and which are connected thereto at their crossings. The 30 lower ends of the members 24 are bent inwardly as at 25 toward the center of the basket to form an openwork bottom therefor. Dishes or other objects placed in the basket are prevented from passing between the ends 25 of the members 24 35 by a ring 26 which is concentric to the rings 23.

The ends 25 of alternate members 24 terminate in a bearing sleeve 27 which is adapted to be mounted on the pin 19 when the basket is positioned in the chamber 11. So that the bearing 40 27 may be readily removed and replaced when it becomes worn, the sleeve 27 has an outwardly extending flange 28 which receives the ends 25 of the members 24. The ends of the members 24 are clamped to the flange 28 and securely 45 held thereon by a washer 29 and nut 30 which is threaded over the sleeve 27. The ends of the remaining members 24 terminate at and are secured to the ring 26.

In order that the rack 18 will freely rotate on 50 the pin 19, the bearing sleeve 28 has openings 31 formed therein which permit the soapy washing water to flow into the sleeve and lubricate the pin 19.

In order that the surface of the dishes will be 55

presented to the scrubbing action of the water, the basket 20 is provided with partitions 32 which hold the dishes on edge in the basket and prevent them from being slapped back and forth against each other. The outer ends of the wire partitions 32 are secured to the rings 23 and in order that the dishes will be held at an angle and act as turbine vanes to rotate the basket, the inner ends of the partitions extend at an angle from the radial center of the basket and are secured to the ring 26. The basket 20 is also provided with vanes 33 which extend downwardly therefrom and are secured to the members 25. The purpose of these vanes will be hereafter explained.

The upper portion of the rack or tray 21 which is adapted to receive the cups, saucers and similar ware, is also of openwork structure, and comprises an upper ring 34 and a lower ring 35 of substantially the same diameter as the rings 23 of the basket 20 and which are connected together by vertically extending members 36 spaced circumferentially around the rings. The lower ends 37 of the members 36 are bent inwardly and extend toward the center of the tray to form an openwork bottom therefor. The inwardly extending ends 37 of alternate members 36 have struck-up portions 38 to provide upwardly extending projections for receiving cups, tumblers and the like, and the extreme inner ends are secured to a ring 39 of such size as to give access to the silverware container 22. Concentric rings 40 are secured to the ends 37 of the members 36 and prevent ware from passing therebetween.

In order that the tray 21 may be readily placed and supported on the basket 20 at three points, a series of members 41 are secured to the lower ring 35 of the tray which are offset adjacent the bottom of the tray to form seats 42 which are adapted to rest on the upper ring 23 of the basket 20.

The silverware container 22 which may be formed of any suitable material and of any desired shape, has a tubular member 43 secured to the bottom thereof which is adapted to fit over the sleeve 28.

When it is desired to operate the dishwasher the basket 20 is placed on the pin 19 and the plates and heavier pieces of tableware are placed thereon between the partitions 32. The tray 21 is then placed on the basket 20 so that the seats 42 on the members 41 rest on the ring 23 and the cups, saucers, tumblers and lighter ware are placed therein. The valve 13 in the drain is then closed and water is poured into the chamber 11 until the vanes 33 on the basket are covered. The motor 16 is then started and the pump 15 draws water from the chamber and forces it through the nozzle 17 so that it impinges against the dishes in the basket 20. This action of the water striking the dishes sets up a scrubbing action and also causes the basket to rotate and the speed of rotation of the basket is controlled by the vanes 33. These retarding vanes prevent the basket from exceeding a certain speed and keep it within limits favorable for dishwashing; that is, limits which will subject the dishes to the most efficient scrubbing action of the water.

It is to be understood that certain modifications may be made herein without departing from the spirit of this invention or the scope of the appended claims.

What I claim as new and desire to secure by Letters Patent is:

1. A dish-supporting basket comprising a series of vertically spaced concentric rings forming the framework of said basket, vertically extending members connecting said rings together and having their lower ends bent toward the center of said rings to form a bottom for said basket, and a sleeve member tying the inwardly extending ends of said members together and forming a center bearing for said basket, said sleeve having an annular flange projecting therefrom and a nut threaded thereon for clamping the ends of said members against said flange. 5

2. In a dishwasher, a rotatable dish-supporting basket comprising a series of concentric rings spaced apart to form an outer openwork frame for said basket, members crossing said rings in circumferentially spaced relation and connected thereto at their crossings, said members having 20 their lower ends bent toward the center for forming an openwork bottom for said basket, removable means for securing the ends of said members together and forming a center bearing for said basket, including a flanged sleeve disposed between the ends of said members and means threaded on said sleeve for clamping the ends to the flange of said sleeve. 25

3. A dish supporting basket comprising a series of vertically spaced concentric rings forming the framework of said basket, a series of spaced vertically extending wires connecting said rings together and having their lower ends bent toward the center of said rings to form a bottom for the basket, a series of curved wires having their ends secured to said vertically spaced rings at regularly spaced intervals and projecting into said basket at an angle to a radial plane through the ends of said wires to provide vertical partitions therein, means for securing the projecting ends 5 of said curved wires to the inwardly bent portions of said first mentioned wires, a sleeve member secured to the inwardly projecting ends of said first mentioned wires and vanes secured to and depending from the inwardly projecting ends of 45 said wires.

4. A dish supporting basket comprising a series of concentrically arranged and vertically spaced rings forming the framework of said basket, a series of wires across said rings in circumferentially spaced relation and connected thereto at their crossings, said wires having their lower ends bent toward the center to form an open-work bottom for the basket, a ring concentrically mounted with but of smaller diameter than said 50 vertically spaced rings secured to the inwardly bent portions of said first mentioned wires a series of curved wires having their ends secured to said vertically spaced rings at regularly spaced intervals around their circumferences, the curved 55 portions of said last mentioned wires projecting into said basket at an angle to the radius thereof to provide vertical partitions therein and being connected to said ring of smaller diameter, a sleeve member removably secured to the inwardly bent ends of some of said first mentioned wires 60 to form a central bearing for the basket and vanes rigidly secured to said first mentioned wires at the point where the wires are bent inwardly toward the center of the basket. 65
